[57] CLAIM

The ornamental design for a telephone, substantially as shown and described.

DESCRIPTION

FIG. 1 is a top front perspective view of a telephone showing my new design;

FIG. 2 is a top plan view thereof;

FIG. 3 is a front elevation thereof;

FIG. 4 is an end elevation thereof;

FIG. 5 is an elevation as seen from the opposite end of FIG. 4;

FIG. 6 is a bottom plan view thereof;

FIG. 7 is a side elevation of the handset separately shown for clarity of illustration;

FIG. 8 is a bottom plan view thereof; and

FIG. 9 is an end elevation thereof, the undisclosed opposite end being a mirror image of the end portion shown.

*FIG. 1**FIG. 2**FIG. 3*FIG. 4
